UNITED STATES PATENT OFFICE.

ROBERT E. EINSTEIN, OF ST. LOUIS, MISSOURI, ASSIGNOR TO THE AMERICAN FLANGE FROG AND RAILWAY IMPROVEMENT COMPANY, OF GAINESVILLE, FLORIDA, A CORPORATION OF FLORIDA.

FLANGE-FROG.

1,339,597.

Specification of Letters Patent. Patented May 11, 1920.

Application filed February 21, 1920. Serial No. 360,301.

To all whom it may concern:

Be it known that I, ROBERT E. EINSTEIN, a citizen of the United States, residing at St. Louis, Missouri, have invented a certain new and useful Improvement in Flange-Frogs, of which the following is a full, clear, and exact description, such as will enable others skilled in the art to which it appertains to make and use the same.

10 This invention relates to railway frogs of the type that are known commercially as "flange frogs", namely, frogs that are provided with a guard member for guiding the flange of a passing wheel past the point of the frog by engaging the tread rim of the wheel in a horizontal plane above the top surface or running surface of the frog.

The main object of my present invention is to increase the efficiency and reduce the 20 cost of manufacture of flange frogs.

Another object is to provide a frog which is of such design that the patterns used in the manufacture of ordinary cast metal frogs and which form one of the main items 25 in the cost of manufacture, can be modified or changed easily so as to adapt them to the manufacture of flange frogs.

Another object is to provide a cast metal frog which is so constructed that the guard 30 members can either be arranged in the ordinary way at opposite sides of the track, or arranged in close proximity to the point of the frog with portions of said guard members projecting above the top surface or running surface of the frog, as is usual in flange frogs.

Another object of my invention is to provide a frog of the particular type referred 40 to, namely, a flange frog that is composed of a cast metal body portion and guard members combined with said body portion, in such a manner that said guard members can be adjusted relatively to the body portion to compensate for wear and can also be reversed and interchanged so as to utilize or bring into service both end portions of each guard member.

Another object is to provide a flange frog 50 that is composed of a cast metal body portion and guard members which reinforce and strengthen said cast metal body portion at the point where said body portion is weakest or most liable to fracture.

Another object is to provide a flange frog 55 that comprises a cast metal body portion that has integral, lateral extensions that sup-

port the guard members of the frog and which provide a relatively great bearing area for the body portion on the ties, thus producing an exceptionally strong and rigid 60 frog that can be held securely to the ties.

And still another object is to provide a flange frog that is composed of a cast metal body portion and separate guard members combined in such a manner that the structure is practically as rigid as a one-piece casting, but is superior to a one-piece casting in that the guard members can be formed from material that is better adapted for the purpose for which the guard members are used. Other objects and desirable features of my invention will be hereinafter pointed out.

Figure 1 of the drawings is a top plan view of a flange frog constructed in accordance with my invention.

Fig. 2 is a transverse sectional view of same, taken on the line A—A of Fig. 1, looking in the direction indicated by the arrows; and

Fig. 3 is a transverse sectional view, 80 taken on the line B—B of Fig. 1, looking in the direction indicated by the arrows.

Referring to the drawings which illustrate the preferred form of my invention, 85 A designates the body portion of the frog which consists of a casting, and B designates the guard members of the frog which have portions that extend above the top surface or running surface of the frog so as to cause 90 the flange of a passing wheel to be guided past the point 1 of the frog by means of a tread rim contact in a horizontal plane above the top surface or running surface of the frog in the manner usual in flange frogs. 95 The body portion A of the frog is similar in general design to the body portion of an ordinary cast metal frog, but it is provided with integral, laterally-projecting extensions or portions on which the guard members B rest and also integral portions that cooperate with the guard members B to overcome the tendency of the guard members to cant when said guard members are subjected to strains produced by the tread rims 105 of the wheels coming in contact with the portions of said guard members that project upwardly above the top surface or running surface of the frog.

In the form of my invention herein shown 110 the body portion A of the frog is provided with two pairs of laterally-projecting ex-

tensions 2 arranged so that they will rest upon two of the track ties α , as shown in Fig. 1. The guard members B are supported by the integral extensions 2 that project laterally from the base of the body portion A, as shown in Figs. 2 and 3, and are clamped securely to said body portion preferably by means of bolts that pass through the guard members B and through the body portion A and by means of clamping elements that lap over the base flanges of the guard members B and clamp them securely to the guard member supporting portions 2 of the body portion A. As previously stated, the body portion A of the frog is preferably provided with means that tends to prevent the guard members B from canting or tilting laterally when they are subjected to a thrust or pressure from a passing wheel. In the form of my invention herein shown said means consists of integral, vertically-disposed ribs or lateral projections 3 on the body portion A that conform to the fishing section of the guard members B and bear snugly against the inner sides of said guard members, as shown in Figs. 2 and 3. It is not essential, however, that the ribs or parts 3 on the body portion A of the casting extend throughout the entire fishing section of the guard members, so long as said ribs 3 comprise portions which bear upon the base flanges of the guard members at the inner sides of same, and thus overcome any tendency of the upper portions of the guard members tilting or canting laterally when said guard members are performing the function for which they are used.

I have herein illustrated the guard members B as being connected to the body portion A of the frog by bolts 4 that pass transversely through said parts in proximity to the toe 1° of the frog, a second set of bolts 5 that pass transversely through the guard members and body portion A in proximity to the point 1 of the frog, and a third set of bolts 6 that pass transversely through the guard members and the body portion A at a point between the toe and point of the frog, as shown in Fig. 1, but it is immaterial, so far as my broad idea is concerned, how the guard members are connected to or combined with the body portion A of the frog. The guard members B can be clamped down upon the lateral extensions 2 on the body portion A by means of clamping devices 7 secured to the lateral extensions 2 by bolts 8 and so designed that they merely lap over the base flanges of the guard members B, or braces 9 can be employed for clamping the guard members downwardly upon the lateral extensions 2 on the cast metal body portion A of the frog, said braces 9 being connected to the lateral extensions 2 on the body portion by

means of bolts 10 and arranged so that the horizontally-disposed bolts 4 and 6 that pass transversely through the guard members and the body portion A also pass through the vertical webs of said braces 9. The extensions 2 on the body portion on which the guard members B are supported are provided at their outer ends with holes 11 through which spikes pass to secure the body portion of the frog to the track ties α , and if desired, said extensions 2 can be provided with integral, upwardly-projecting ribs or flanges 12 that coöperate with the base clamps 7 or 9 to resist the lateral thrusts to which said base clamps are subjected when a wheel passes over the frog.

The guard members B may consist of forged or cast members, or they may consist of pieces of ordinary T rail. Each of said guard members is provided with a straight central portion and flared end portions 13 which extend at an angle to said central portion, the guard members B being so arranged with relation to the point 1 of the frog that one of the flared end portions of each guard member extends parallel to the adjacent face of the frog point, as shown in Fig. 1. The openings in the webs of the guard members B through which the retaining bolts 4 and 6 pass are similarly located and are formed equidistant from each other, and the openings in the webs of the flared end portions 13 of the guard members are also similarly located and are formed equidistant from each other. As each guard member is of regular form and as both ends of same are symmetrical and of the same angle, the guard members can be turned end for end and arranged at opposite sides of the point of the frog so as to bring the unworn end portions of said guard members into service after the portions of said guard members that are arranged in proximity to the frog point 1 have become worn. The webs of the guard members B are also provided with additional sets of bolt holes indicated by the reference character 14 in Fig. 1, so that when a guard member becomes worn, the securing bolts for same can be removed and said guard member adjusted longitudinally toward the toe 1° of the frog to bring the engaging face of said guard member closer to the running line of the frog, and thus compensate for wear.

A flange frog of the construction above described is exceedingly efficient, as it comprises a cast metal body portion and guard members that can be easily adjusted to compensate for wear and to bring fresh, unworn portions of said guard members into service after the parts of same that are arranged in proximity to the point of the frog have become worn. It is stronger than an ordinary cast metal frog, due to the fact that the guard members embrace the cast metal body

- portion throughout the major part of the length of same and are securely connected to said body portion by through bolts in proximity to the points where the body portion is weakest and most liable to fracture. Moreover, the body portion of my improved frog has a relatively great bearing area on the ties, due, of course, to the fact that the body portion has integral, lateral extensions 2 that rest upon the ties, and it can be spiked or connected to the ties so securely that it will not work loose quickly. The ribs or projections 3 on the body portion A of the frog that conform to the fishing sections of the guard members reduce the tendency of the guard members to tilt or cant laterally, and as said guard members are secured to the body portion of the frog by means of through bolts and by clamps that hold said guard members down upon the lateral extensions 2 on the body portion, the structure is practically as rigid as a one-piece casting, but is superior to a single casting, in that the guard members and the running surface of the frog can be formed from material that is particularly suited to the work for which said parts are used. In addition to the desirable features above pointed out, a flange frog of the construction herein illustrated can be manufactured cheaply, due to the fact that the patterns used in the manufacture of ordinary cast metal frogs and which form one of the principal items in the cost of manufacture, can be changed or modified easily to adapt them to the manufacture of my improved frog by simply adding parts to the pattern so as to form the lateral extensions 2 on the body portion and the vertical ribs or projections 3. While the body portion A of the frog is so designed that the guard members 5 can be arranged in close proximity to the point of the frog with portions of said guard members projecting above the running surface of the frog so as to produce what is commercially known as a "flange frog", still it is not essential that the guard members be arranged in this manner for if desired, they can be arranged at opposite sides of the track, as is usual with the ordinary railway frog.
- Having thus described my invention, what I claim as new and desire to secure by Letters Patent, is:
1. A flange frog, comprising a cast metal body portion and a separate guard member detachably connected to said body portion and provided with a wheel rim engaging portion arranged above the top surface or running surface of the frog.
2. A flange frog, comprising a cast metal body portion, and guard members separate and distinct from said body portion and provided with wheel rim engaging portions ar-
- ranged in a higher horizontal plane than the top face of said body portion.
3. A flange frog, comprising a cast metal body portion, a guard member combined with said body portion and provided with a wheel rim engaging portion arranged in a higher horizontal plane than the top face of said body portion, and an integral extension on said body portion that supports said guard member.
4. A flange frog, comprising a cast metal body portion, a guard member combined with said body portion and provided with a wheel rim engaging portion arranged in a higher horizontal plane than the top face of said body portion, an integral extension on said body portion that supports said guard member, an integral means on said body portion that engages said guard member and resists strains on said guard member in a direction tending to cant said member.
5. A flange frog, comprising a cast metal body portion provided with an integral, laterally-projecting extension, a guard member supported by said extension and provided with a wheel rim engaging portion that is arranged in a higher horizontal plane than the top surface of said body portion, and means for preventing said guard member from rising upwardly off of said extension when said guard member is subjected to pressure from a passing wheel.
6. A flange frog, comprising a cast metal body portion, a guard member connected to said body portion and provided with a wheel rim engaging portion arranged in a higher horizontal plane than the top surface of said body portion, an integral part on said body portion on which said guard member rests, an integral part on said body portion that resists strains on said guard member in a direction tending to cant said guard member, and means for clamping said guard member to the part of said body portion on which said guard member rests.
7. A flange frog, comprising a cast metal body portion, a guard member extending longitudinally along one side of said body portion and provided with a wheel rim engaging portion arranged in a higher horizontal plane than the top face of said body portion, a part on said body portion on which said guard member rests, a surface on the side of said body portion that conforms to a portion of the inner side of said guard member, and means for clamping said guard member to said body portion.
8. A flange frog, comprising a cast metal body portion, guard members embracing said body portion and provided with wheel rim engaging portions that are arranged in a higher horizontal plane than the top side of said body portion, and integral exten-

- sions on said body portion that support said guard members and bear upon the track ties.
9. A flange frog, comprising a cast metal body portion, guard members embracing said body portion and provided with wheel rim engaging portions that are arranged in a higher horizontal plane than the top side of said body portion, integral extensions on said body portion that support said guard members and bear upon the track ties, devices that clamp said guard members to said extensions, and integral ribs on said body portion that bear against the inner sides of said guard members.
10. A flange frog, comprising a cast metal body portion provided with a point and a toe, guard members that embrace said body portion and which are provided with wheel rim engaging portions arranged in a higher horizontal plane than the top side of said body portion, and means for bolting said elements together at points in proximity to the toe and point of the frog.
11. A flange frog, comprising a cast metal body portion provided with integral, laterally-projecting extensions that rest upon the track ties, guard members embracing said body portion and provided with wheel rim engaging portions that are arranged in a higher horizontal plane than the running surface of the frog, integral ribs on said body portion that bear on the inner sides of said guard members, and clamps on said extensions that lap over the base flanges of said guard members.
12. A frog provided with a cast metal

body portion having integral extensions that project laterally from the base of same at points in proximity to the toe and point of the frog for supporting guard members.

13. A frog provided with a cast metal body portion equipped with integral means that are adapted to support guard members and resist strains on said guard members in a direction tending to cant said members.

14. A flange frog, comprising a cast metal body portion, and adjustable guard members combined with said body portion and provided with wheel rim engaging portions arranged in a higher horizontal plane than the running surface of the frog.

15. A flange frog, comprising a cast metal body portion, and guard members combined with said body portion and constructed in such a manner that they can be reversed and arranged at opposite sides of the point of the frog.

16. A flange frog, comprising a cast metal body portion, and guard members combined with said body portion in such a manner that they can be adjusted longitudinally of the frog to compensate for wear and can also be reversed and arranged at opposite sides of the point of the frog.

17. A flange frog, comprising a cast metal body portion, and a guard member supported by said body portion and comprising a straight intermediate part and flared end portions, one of which end portions is arranged parallel to one side of the point of the frog.

ROBERT E. EINSTEIN.
